UNITED STATES PATENT OFFICE.

HARRY LEAP, OF CAMP MEEKER, CALIFORNIA.

WHEEL-DIRECTION INDICATOR.

1,165,186.

Specification of Letters Patent. Patented Dec. 21, 1915.

Application filed August 31, 1914. Serial No. 859,419.

To all whom it may concern:

Be it known that I, HARRY LEAP, a citizen of the United States, residing at Camp Meeker, in the county of Sonoma and State 5 of California, have invented new and useful Improvements in Wheel-Direction Indicators, of which the following is a specification.

This invention relates to a wheel direction indicator for automobiles.

Drivers of automobiles often find it not only desirable but sometimes of considerable importance to know the position or direction in which the front wheels of the car are 15 pointing when starting up and moving away from a difficult place or position where considerable maneuvering is necessary, or when a foot or two in the wrong direction may prove more or less disastrous. Similar 20 difficulties are also encountered where heavy sand or mud has to be contended with.

The object of the present invention is to overcome this difficulty by providing a simple form of wheel direction indicator for 25 automobiles, which is adapted to be placed in a position within convenient and constant view of the driver, and to provide a connection between the indicator and the steering mechanism of the automobile whereby every 30 movement of the steering mechanism will be directly transmitted to the indicator, thus indicating at all times the position of the front wheels.

Further objects will hereinafter appear.

35 The invention consists of the parts and the combination and construction of parts as hereinafter more fully described and claimed, having reference to the accompanying drawings, in which—

40 Figure 1 is a side elevation of a car showing the application of the invention. Fig. 2 is a perspective detail view of the connection formed between the indicator and the steering mechanism.

45 A indicates in general a car, 2 the front wheels and 3 the standard form of steering knuckles which are connected by the tie rod 4.

50 Suitably secured on top of one of the mud guards 5, is a flanged bearing member 6 and turnably mounted in same is a shaft 7 which projects down through the mud guard. Secured on the upper end of said shaft is an

arrow or direction indicator 8, and secured to the lower end of the shaft, just below the 55 mud guard, is a crank arm 9. This crank arm is adapted to turn the shaft upon which the direction indicator or arrow 8 is mounted by the following connections formed between same and the steering mechanism. 60 Suitably secured to the tie rod 4 at one end, as at 10, and on the other end to the crank arm, as at 11, is a flexible cable 12. This cable passes over direction pulleys 13 and 14, which are placed in suitable positions to 65 give the cable the necessary and desired direction. The other side of the crank arm is connected to a coil spring 15, which has a tendency to normally pull the arm in the direction of arrow a.

70 The operation will be as follows: Any movement of the steering knuckles, with connected tie rod 4, in the direction of arrow b, will, in this instance be transmitted through the flexible cable which passes over direction pulleys 13 and 14 to the crank arm 9 and pull this in the direction of arrow c, while movement of the tie rod in the opposite direction to arrow b will permit the flexible cable to slacken and allow the tension of spring 15 to pull the crank arm in the direction of arrow a. The vertical shaft 7 with connected direction indicator or arrow 8 is thus turned in both instances in unison with the steering mechanism and 80 front wheels and will thus constantly indicate the position of same.

85 While I have here shown the indicating mechanism as being mounted on the mud guard, it is obvious that it may be mounted 90 in any other suitable position, and that various connections between same and the steering mechanism may be provided without departing from the spirit of the invention.

95 The materials and finish of the several parts of the device are such as the experience and judgment of the manufacturer may dictate.

Having thus described my invention, what 10 I claim and desire to secure by Letters Patent is—

The combination with the front wheels, steering knuckles and connected tie rod on an automobile, of a bearing member, a shaft 10 turnably mounted in same, a crank arm se-

cured on the lower end of the shaft, an indicating pointer on the other end, a cable connected at one end with the tie rod and at the other with the crank arm to transmit the movement of the tie rod, direction pulleys over which the cable passes, and a coil spring connected with the crank arm.

In testimony whereof I have hereunto set my hand in the presence of two subscribing witnesses.

HARRY LEAP.
